Fig. 7.

INVENTOR:
George F. Voight.

UNITED STATES PATENT OFFICE.

GEORGE F. VOIGHT, OF OAKLAND, CALIFORNIA.

STUCCO-WIRE CLIP.

Application filed March 6, 1923. Serial No. 623,210.

My invention relates to stucco wire particularly adapted for reinforcing and securing stucco, concrete and other plastic materials to the sheathing boards and walls of frame buildings, although also useful for other purposes.

One of the objects of the present invention is the provision of stucco wire having furring clips fixedly attached in regular spaced apart order, whereby said wire may be readily attached to the sheathing boards of frame structures in uniform outstanding relation therewith by simply driving ordinary nails through the clips and into the sheathing boards.

A further object is the provision of stucco wire having furring clips rigidly attached at regular intervals along its edges, whereby the wire may be drawn taut in cross section by inserting nails in openings provided in the clips, and using the nails as levers for prying the edges of the wire outwardly, after which the nails may be driven into the sheathing boards for securing the wire thus stretched permanently thereto.

With the foregoing and still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:

Figure 1 is a face view of a section of stucco wire constructed in accordance with my invention, attached to the sheathing boards of a frame building.

Figure 2 is an enlarged view of a portion of the netting shown in the preceding figure.

Figure 3 is the wire designated by "b" in Fig. 2, disassembled.

Figure 4 is a sectional elevation on line 4-4, Fig. 2.

Figure 5 is a sectional view on line 5-5, Fig. 2.

Figure 6 is a view in elevation of a blank stamping of sheet metal from which the clips are formed.

Figure 7 is a perspective view of one of the furring clips removed from the grille; the view showing a slight modification in

that there are provided a plurality of nail openings instead of a single opening as provided in the preferred form of the device.

Referring to the drawings in detail, 60 throughout which like reference characters designate like parts:

The numeral 1 designates a wire grille corresponding in general construction to what is commonly known as poultry netting 65 and comprises intermediate mesh wires 2, marginal mesh wires 2^a and marginal cables 3.

The mesh wires 2 and 2^a are crimped in staggered order in both directions laterally 70 in the plane of the grille (see Fig. 3), thereby forming alternately opposed curled apexes 4, which in the intermediate wires 2 are wound around the registering and corresponding apexes of the two co-engaging 75 wires on either side, thereby forming inter-twisted portions 5 constituting the upper and lower median sides of open meshes 6, while in the marginal mesh wires 2^a the inner apexes are likewise wound around the 80 registering and engaging apexes of the succeeding wire thereby forming like inter-twisted portions 5, and outer apexes wound around the marginal cables 3 at regular spaced apart intervals, thereby forming 85 marginal inter-twisted portions 5^a, meshes 6 and relatively restricted meshes 6^a.

In the drawings, the marginal cables 3 are shown to comprise single wires substantially larger diametrically than the mesh 90 wires 2 and 2^a. However, if desired, the cable and mesh wires may be of one size, and furthermore, if preferred, the cables 3 may be composed of two or more wires each, either twisted together or in parallel en- 95 gagement.

7 designates the furring clips, a blank stamping of one of which is shown in Fig. 6. Each of which clips comprising a bridge member 8 having a central nail opening 9, 100 a pair of downwardly struck oppositely disposed side limbs 10, and at either end an extension 11 which is rolled back upon the bridge member 8 to form loops 11^a encircling oppositely disposed inter-twisted portions 5 when the clip is attached to a mesh 105 formed of the intermediate wires 2, and encircling one of the portions 5 and a corresponding inter-twisted portion 5^a when the clip is attached to the margin of the grille. 110

It will be observed that in Fig. 7 there appear three nail openings in the bridge mem-

- ber 8. The number of these openings are left to the option of the manufacturer and user of the grille. The purpose of any opening in the bridge is to receive the shank 5 of a fastening nail, the head of which is intended to seat upon the upper side of the bridge while the free end of the shank is projected a proper distance into the sheathing boards or other support to which the grille may be operatively secured. The numeral 12 designates a nail disposed as aforesaid, and the numeral 13 designates the sheathing or support to which the grille is secured.
- 15 I have found in practice, that convenient dimensions for the netting are a width of about three feet with a length of twenty-five to fifty feet, although any other suitable or preferred dimensions may be adopted 20 in its construction.
- The furring clips 7, which are intended to be factory-built into the wire 1, may be spaced along on the latter as may be found best suited for the work to be performed.
- 25 And in applying the wire it is simply necessary to spread it across the face of the sheathing boards and drive ordinary nails thereinto through the openings 9 in the clips 7. To stretch the wire in any direction parallel 30 with the sheathing boards, the forward end of the nail after it has been inserted in the opening in the clip, is inclined in the direction in which it is desired to stretch the wire and then fulcrumed against the sheathing, after which the nail may be used 35 in the manner of a lever by thrusting its upper end over in the same direction, thereby causing the clip and wire to move likewise proportionately.
- 40 The clips 7 are intended to provide furring means for spacing the wire a predetermined distance from the face of the sheathing boards, as well as securing means for securing it thereagainst.
- 45 The several clips attached to a section of the wire are intended to project through from the same side, thus disposing the free ends of the limbs 10 in a plane extending parallel with the plane of the wire.
- 50 I claim:
1. A furring clip comprising, an intermediate bridge member having an opening therethrough, extensions on the ends thereof adapted to be fixedly attached to spaced portions 55 of stucco wire, a side limb on one edge of said bridge member, the free edge of said side limb adapted to seat against the sheathing boards of a structure for holding said bridge member and said stucco wire in spaced relation therewith, and a co-operating nail projecting through said opening and along one side of said side limb, said nail having head seated against the upper side of said bridge member, the forward end 60 of said nail projecting beyond said free edge

of the side limb, said forward end of the nail adapted to be projected into said sheathing boards for binding the clip thereagainst.

2. A furring clip comprising, an intermediate bridge member having an opening therethrough from the upper to the lower side thereof, extensions on the ends of said bridge member adapted to be attached to laterally spaced portions of stucco wire, a pair of side limbs on said bridge member, the free edges of said side limbs adapted to seat against sheathing boards and when thus seated to be disposed in parallel planes at right angles with the face side of said sheathing boards, and a cooperating nail projecting through said opening and between said side limbs, said nail having a head seated against one side of said bridge member, the forward end of said nail projecting out beyond said free edges of the side limbs, said forward end of the nail adapted to be projected in the sheathing boards for binding the side limbs thereagainst.

3. A furring clip comprising, a bridge member having a nail opening therethrough, opposite ends of said bridge member terminating in loops adapted to embrace laterally spaced portions of stucco wire for rigidly attaching the furring clip thereto, a side limb on said bridge member, said side limb adapted to seat against sheathing boards for supporting said bridge member in spaced relation therewith, and a co-operating nail projecting through said nail opening and along one side of said side limb, the forward end of said nail projecting outwardly beyond the free edge of said side limb, said forward end adapted to be driven in said sheathing boards for holding said clip against the face side thereof.

4. A furring clip formed of a strip of sheet metal and comprising, an intermediate bridge member having a nail opening, means integral with said bridge member adapted to seat against the sheathing boards of a structure for supporting said bridge member in outwardly spaced relation therewith, opposed ends of said bridge member fixedly attached to spaced portions of stucco wire, and a nail projecting through said nail opening and along side of said means, the forward end of the nail projecting out beyond the free end of said means, said forward end of the nail adapted to be projected in said sheathing boards for binding the clip against the face side thereof, said nail having a head seated against the outer side of said bridge member, said head and bridge member being approximately in the plane of said stucco wire.

5. A furring clip comprising an intermediate member having opposite ends fixedly attached to spaced portions of stucco wire, and means integral with said intermediate member, said means having a portion adapt-

ed to seat against a support for holding said intermediate member in spaced relation thereto, said intermediate member having an opening adapted to receive a nail, 5 said nail adapted to be projected in said support a distance for binding said clip thereagainst.

6. A furring clip embodying an intermediate member having opposite ends fixedly 10 attached to spaced portions of stucco wire, and a side limb integral with said intermediate member between said ends, said side limb adapted to seat against a support for holding said intermediate member and said 15 stucco wire spaced therefrom, said inter-

mediate member having an opening between said ends, said opening adapted to receive a separately applied nail having a head, said nail adapted to be projected in said support for seating said head against said intermediate member for binding said clip against said support, said nail being free from contact with said stucco wire when projected in said support for binding the clip thereagainst. 20

In testimony of the foregoing being my own, I have hereunto affixed my signature this 24th day of February, 1923. 25

GEORGE F. VOIGHT.
